INVENTOR

BY Victor J. Evans

ATTORNEY

UNITED STATES PATENT OFFICE

THOMAS C. DUNCAN, OF PORTSMOUTH, VIRGINIA

FIRE ALARM

Application filed September 5, 1930. Serial No. 479,989.

This invention relates to a fire alarm, the general object of the invention being to provide a casing containing explosive material, with means whereby the casing can be attached to a wall, roof, ceiling or any other place where a fire is likely to occur, so that if a fire should occur at this point, the device will explode and thereby notify persons that a fire has broken out.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:

Figure 1 is a side view showing the device attached to a wall.

Figure 2 is a front view of the device.

Figure 3 is a section on line 3-3 of Figure 2.

In these drawings, the numeral 1 indicates a casing formed of any suitable material and containing explosive material 2. One end of the casing is closed by the plug 3 and a fuse 4 passes through the plug and has one end embedded in the explosive material and its other end projecting from the device. The other end of the casing is flattened at its front, as shown at 5, with a hole 6 formed therein so that a nail 7 or the like can be passed through the hole to fasten the device to a wall or other support, as shown in Figure 1.

A cover 8 encloses the device and has its lower end extended to enclose the projecting end of the fuse, as shown at 9. This cover is preferably formed of celluloid which protects the device from moisture and the like and which also acts to cause the fuse to be quickly ignited if a fire should occur near the device, due to the combustibility of the celluloid. The upper end of the cover 8 conforms to the shape of the upper end of the device, as shown.

Thus I have provided a simple form of fire alarm which can be manufactured to sell

at low cost so that a number of these devices can be bought at a low price and placed at various parts of a building. If a fire should break out near one of these devices, the fuse would be quickly ignited and the resultant explosion would notify persons that the building is on fire.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:

A device of the class described comprising a casing having explosive material therein, a fuse passing through one end of the casing and projecting therefrom, the other end of the casing being flattened and having a hole therein for receiving a nail or the like to fasten the device to a support and a covering of inflammable and waterproof material fitting over the casing and having one end extended and enclosing the projecting part of the fuse.

In testimony whereof I affix my signature.

THOMAS C. DUNCAN.
